CLAIM

The ornamental design for a lamp base, as shown and described.

DESCRIPTION

FIG. 1 is a top perspective view of a lamp base, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a top perspective view of a lamp base in a position of use with broken line environment.

The broken lines show portions of the lamp base that form no part of the claimed design in FIGS. 1, 6, 7, and 9. The broken lines also show environmental subject matter that form no part of the claimed design in FIG. 9.
